UNITED STATES PATENT OFFICE.

JOHN T. GREENE, OF TOLEDO, OHIO, ASSIGNOR TO THE NATIONAL ELECTRIC
SPECIALTY COMPANY, OF TOLEDO, OHIO, A CORPORATION OF OHIO.

PROTECTIVE APPARATUS FOR ELECTRICAL INSTRUMENTS.

1,178,713.

Specification of Letters Patent. Patented Apr. 11, 1916.

Application filed March 2, 1914. Serial No. 822,009.

To all whom it may concern:

Be it known that I, JOHN T. GREENE, a citizen of the United States, residing at Toledo, in the county of Lucas and State of Ohio, have invented certain new and useful Improvements in Protective Apparatus for Electrical Instruments, of which the following is a specification.

My invention relates to protective apparatus for electrical instruments, and the invention has for a primary object to provide an electrical instrument with protective apparatus consisting of a plurality of devices which become operative under somewhat 15 different conditions to safe-guard the instrument against abnormal currents and disturbances of various sorts due, for example, to lightning discharges and crosses with high power circuits, which devices are constructed and arranged so that one protects the other and so that in case one should become inoperative the other or others will give a measure of protection, at least, to the instrument with which said apparatus is 25 associated.

A further object of the invention is to provide an apparatus of this character which will be compact in form, economical to manufacture, conveniently installed, and 30 so constructed that the parts requiring occasional renewal may be easily replaced without disturbing the other parts of the apparatus.

The invention has for further objects such other new and improved constructions, arrangements and devices relating to the protection of electrical instruments from abnormal currents and disturbances as will be hereinafter described and claimed.

40 The invention is shown in the accompanying drawings as embodied in a preferred form of apparatus.

In the drawings Figure 1 is a plan view of the apparatus; Fig. 2, a side elevation of the same; Fig. 3, a sectional view taken on line 3—3 of Fig. 1; Fig. 4, a fragmentary sectional view on line 4—4 of Fig. 1, and Fig. 5, a diagram to show the electrical connections.

50 Like characters of reference designate like parts in the several figures of the drawings.

Referring to the drawings, 10 designates a base which may be permanently affixed to a switch-board signal box or other support, 55 designated 11, by the bolts 12. The par-

ticular form of apparatus shown is intended to protect two instruments A, A' through a single ground wire 13. The base member 10 is, therefore, provided with two pairs of line wire terminals 14, 15 and 14', 15'. Mounted 60 on the base adjacent terminal 14, and electrically connected therewith by the metal strip 16, is a spring clip or jack 17. Similarly a spring clip or jack 18 is mounted on the base near the terminal 15 and electrically connected therewith by means of the metal strip 19, 19'. A similar pair of clips 17', 18' are associated with terminals 14', 15'. These clips are adapted to receive fuses 20, 20' of any suitable construction. 70

The grounded wire 13 is carried up through a groove 21 in the side of the base member 10 to a binding post 22 arranged between the fuses 20, 20'. The aerials 23, 23' may be connected with either pair of terminals 14, 14', or 15, 15'. I have shown them as connected with the terminals 14, 14', the instruments A, A' being connected with the other pair of terminals 15, 15' by wires designated 24, 24'. 80

25 designates the evacuated bulb of a vacuum arrester having two line wire electrodes 26, 26' and a single ground electrode 27. The bulb 25 is mounted on a base member 28 detachably secured to the base 10 by 85 means providing electrical connections between electrodes 26, 26', 27 and binding posts 15, 15', 22, as follows: The leading-in wires 29, 29' for electrodes 26, 26' are connected with U-shaped clips 30, 30' secured 90 to the base member 28 by screws 31. These clips are adapted to project into spring jacks 32, 32' fitted into recesses in the base 10 secured to the base by screws 33 and electrically connected with the binding posts 95 15, 15', respectively, by the angular metal strips 34. The leading-in wire 35 of the ground electrode 27 is connected with a strip 36 secured to the base member 28 by screw 37 and formed at its outer end with a slot 38 for a bolt 39 on the base 10. The mechanical and electrical connections are completed by nuts 40 and by a wire 41 connecting bolt 39 to the binding post 22. 100

The apparatus preferably comprises 105 means for providing an air spark gap for each line which will be operative to ground the current in case of abnormal voltage if the normal means for taking care of the disturbance, the gap *in vacuo*, is for any reason 110

ineffective. To this end I provide sparking points 42 42' adjustably mounted on the ends of the strips 19, 19' by means of bolts 43 and nuts 44, the sparking points coming close to, but without touching, the corners of a plate 45 associated with the ground terminal 22. The elements 42, 42' being mounted so that they may be turned on the bolts 43 makes it possible to employ the air gaps or not as may be desirable in a particular case, and when this auxiliary protection is desirable permits the gaps to be adjusted.

The operation of the apparatus above described is as follows: If the disturbance on one of the aerials, say wire 23, is of short duration, even though it may have a very high voltage, such for example as is produced by the ordinary lightning discharge, the current will pass through the fuse 20 without burning it out but will be grounded by the vacuum arrester. If the abnormal charge be of considerable duration, for example as might occur from a cross between line 23 and a trolley wire or other high power circuit, and this be allowed to go to the vacuum arrester, the result would be likely to be the burning out of the arrester resulting either in a permanent ground through the arrester or the destruction of the instrument intended to be protected. Under these circumstances, however, with the arrangement I have shown, fuse 20 will burn out so that both the instrument and the vacuum arrester will be saved. If desired the wires 23, 23' may be connected with binding posts 15, 15' and the wires 24, 24' with binding posts 14, 14'. In this arrangement, however, the vacuum arrester would not be as well protected.

It will be seen that the apparatus above described is extremely compact. Each unit serves two circuits through a single ground. By multiplying the units and placing them side by side on the switch-board or other support, a large number of instruments can be protected by apparatus which occupies but little space. The parts likely to require occasional replacement, the fuses and the vacuum arrester, may be replaced and renewed without disturbing the wiring or other parts of the apparatus. To remove the vacuum arrester it is only necessary to unscrew nuts 40 and detach the base members 28 from the base 10 by pulling clips 30, 30' from the spring jacks which they normally engage.

A further protection to the instrument is afforded by the air gap provided by elements 42, 45. The adjustment of the element 42 is intended to give the gap between it and the grounded element 45 a resistance higher than the normal resistance of the vacuum gap. The air gap, however, becomes effective to ground an abnormal charge if,

for any reason, the vacuum arrester fails to perform this function.

While I have described my invention in certain preferred embodiment, it will be understood that as modifications might be made without departing from the principles of the invention I do not wish to limit the invention to the particulars described and claimed except so far as they are made specific limitations in certain of the claims appended hereto.

I claim:

1. In protective apparatus for an electrically operated instrument, the combination with a fixed base member, of a pair of line wire terminals on said base member, a pair of fused clips connected with said terminals, respectively, a ground line terminal, an adjustable element connected with one of said clips which projects close to but without touching said ground wire terminal, an arrester comprising an evacuated vessel and spaced electrodes therein, a base member on which said arrester is mounted, and means for detachably securing this base member to the fixed base member, which means provides electrical connections between said electrodes and the terminals on said fixed base member.

2. In protective apparatus for an electrically operated instrument, the combination with a fixed base member, of a pair of line wire terminals on said base member, a pair of fused clips connected with said terminals, respectively, a ground wire terminal, an arrester comprising an evacuated vessel and spaced electrodes, a base member on which said arrester is mounted, and means for detachably securing the last mentioned base member to said fixed member, which means provides electrical connections between said electrodes and the terminals on said fixed base member.

3. In protective apparatus for an electrically operated instrument, the combination with a fixed base member, of two pairs of line wire terminals on said base member, two pairs of fuse clips electrically connected with said pairs of terminals, respectively, a single ground wire terminal, an arrester comprising an evacuated vessel having mounted therein a pair of line electrodes and a single mounted electrode, a base member on which said arrester is mounted, and means for detachably securing said last mentioned base member to the fixed base member, which means provides electrical connections between said electrodes and the terminals on said fixed base member.

4. In protective apparatus for an electrically operated instrument, the combination with a fixed base member, of two pairs of line wire terminals on said base member, two pairs of fuse clips electrically connected with said pairs of terminals, respectively, a single ground wire terminal, and arrested compris-

ing an evacuated vessel having mounted therein a pair of line electrodes and a single mounted electrode, a base member on which said arrester is mounted, means for detachably securing said last mentioned base member to the fixed base member, which means provides electrical connections between said electrodes and the terminals on said fixed base member, sparking points connected each with one of each pair of fuse clips and revolvably mounted on said fixed base member, and an angular plate associated with the grounded terminal arranged so that the sparking points come into proximity without touching the corners thereof.

5. In protective apparatus for an electri-

cally operated instrument, the combination with a base member, of two pairs of line wire terminals on said base member, two pairs of fused clips electrically connected with said pairs of terminals respectively, a single ground wire terminal, an arrester comprising an evacuated vessel having mounted therein a pair of line electrodes and a single grounded electrode, and means for detachably securing said arrester to the base member, which means provides electrical connections between said electrodes and their respective terminals on said base member. 20 25 30

Correction in Letters Patent No. 1,178,713.

It is hereby certified that in Letters Patent No. 1,178,713, granted April 11, 1916, upon the application of John T. Greene, of Toledo, Ohio, for an improvement in "Protective Apparatus for Electrical Instruments," an error appears in the printed specification requiring correction as follows: Page 2, line 130, claim 4, for the words "and arrested" read *an arrester*; and that the said Letters Patent should be read with this correction therein that the same may conform to the record of the case in the Patent Office.

Signed and sealed this 23d day of May, A. D., 1916.
